FILING EQUIPMENT

Claude B. Cooper, Watertown, Mass.

Application April 3, 1930. Serial No. 441,379

11 Claims. (Cl. 129—16)

This invention relates to filing equipment for the vertical filing of papers, usually in folders. Heretofore, in the drawers of filing cabinets, reliance has been placed on an adjustable follower 5 at the rear of the folders, to maintain the latter in an upright position. But this practice is not wholly satisfactory, as it requires too frequent and too accurate adjustment of the follower to maintain the uprightness of the folders. If with 10 frequent removal and replacement of folders the adjustment of the follower is neglected, as is usually the case, files will fall over into a more or less horizontal position. The present invention deals with novel means to maintain the upright position of the folders, without the need of frequent or accurate adjustment of the follower.

The invention will best be understood by reference to the following description, when taken 20 in connection with the accompanying drawing of one specific embodiment thereof, while its scope will be pointed out more particularly in the appended claims.

In the drawing:

25 Fig. 1 is a vertical, cross-sectional view of a filing cabinet drawer, in connection with which my invention is illustrated;

Fig. 2 is a vertical, longitudinal section, on line 2—2 of Fig. 1;

30 Fig. 3 is a horizontal section on line 3—3 of Fig. 1; and

Fig. 4 is a horizontal, sectional view on line 4—4 of Fig. 1.

Referring to the drawing, and to the embodiment of the invention which is illustrated therein, there is shown a drawer having a bottom 5, and two side walls 6, of well-known form, the bottom being provided with a longitudinal depression 7, which receives a channel member 8 35 extending lengthwise of the drawer, and provided with inwardly-directed flanges 9 to receive a usual follower 10. A series of vertical folders 11 occupy most of the space between the follower and the front of the drawer.

40 At one or more, herein several points along the drawer, in accordance with this invention, there are provided members 12 extending transversely of and above the side walls 6, and supported by the latter. Each of these members is in the 45 nature of an auxiliary follower, which can be placed at any desired point very quickly and conveniently. To prevent sidewise movement of the member 12, the latter herein is provided with two shoulders 13, which are received between the 50 side walls 6, and with ample clearance to per-

mit said member to be moved lengthwise of the drawer without inconvenience. Herein, there is a second shoulder 14 at the outer side of the side wall 6, but in some cases, this may be dispensed with. Two friction reducing rollers 15, resting upon the upper edges of the side walls 6, are mounted to turn on fixed studs 16, conveniently secured to the member 12, as by making the stud bifurcated to embrace said member, while a rivet 17, extending through the stud and through said member, secures the stud in place. The presence of the shoulder 14 prevents the roller from becoming detached from the stud.

Upward displacement of the member 12 is prevented by appropriate means, herein an anchor member 18, suitably attached to the drawer below the member 12, as by providing the member 18 with arms 19 disposed beneath the flanges 9 of the channel bar 8. The introduction of the anchor member into its place is conveniently accomplished in the present example in the manner illustrated in Fig. 3, which shows the anchor member in dotted lines in its preliminary position, prior to engagement with the channels. The anchor member is simply turned from the position shown in dotted lines to that shown in full lines, thus bringing its arms beneath the flanges.

80 The anchor member is suitably connected to the member 12, as by resilient means, herein springs 20, which urge the member 12 downwardly toward the side walls 6. These springs are conveniently attached to the anchor member, as by having their lower ends coiled about the anchor member, as at 21, while their upper ends are conveniently attached to the member 12, by providing the latter with holes 22, through which terminal portions of the wires are passed, and then coiled about the main portions of the wires, as at 23. These springs not only tend to prevent upward displacement of the member 12, but also to center the latter above the anchor 18, while at the same time allowing slight resilient yielding of the members 12 along the track presented by the side walls 6 of the drawer. Moreover, the springs render the follower vertically extensible, and thus enable the anchor member to be attached to the lower guide, while the member 12 is resting upon the drawer sides.

100 The device is capable of being applied to the drawer quickly and conveniently by first placing the member 12 in its proper position, then pushing downwardly upon the anchor member, thus extending the device vertically by stressing the springs, and finally attaching the anchor 105

110

member in the manner already described. Adjustment of the whole device lengthwise of the drawer can be accomplished conveniently by sliding the anchor member along the channel member. Naturally, the stress of the springs tends to maintain the anchor member in the position to which it has been adjusted.

The number of devices used in the drawer will naturally depend upon the number of folders, and 10 the distance of the follower from the front end of the drawer. If at first there are comparatively few folders, one of the devices will suffice, but as the number of folders is increased, the number of the devices can be increased correspondingly, until the drawer when fairly well filled 15 will contain perhaps three or four of the devices. As shown in Fig. 2, the devices are, in a way, auxiliary followers, which serve as partitions to maintain substantially upright positions 20 of the folders, without the necessity of frequent or accurate adjustment of the follower.

Having thus described one embodiment of my 25 invention, but without limiting myself thereto, what I claim and desire by Letters Patent to secure is:

1. In a file, the combination of a drawer having 30 side walls, a member extending transversely of and above said side walls and supported by the latter, and resilient means tending to urge said member downwardly toward said side walls.

2. In a file, the combination of a drawer having 35 side walls, a member extending transversely of and above said side walls and supported by the latter, a member adjustable lengthwise of said drawer, below the first-mentioned member, and resilient means connecting said members and urging the first-mentioned member downwardly toward said side walls.

3. In a file, the combination of a drawer having 40 side walls and a longitudinal guide, a member engaged with and adjustable longitudinally of said guide, a member extending transversely of and above said walls and supported by the latter, and vertically extensible means connecting said 45 members to each other and tending to prevent upward displacement of the second-mentioned member.

4. In a file, the combination of a drawer having 50 side walls and a longitudinal guide, and a vertically extensible device adjustable lengthwise of said drawer and guided partly by the upper edges of said side walls and partly by said 55 guide.

5. In a file, the combination of a drawer having 60 side walls, a member extending transversely of and supported by said side walls, and resili-

ent means urging said member downwardly toward said side walls.

6. In a file, the combination of a drawer having 80 side walls, a member extending transversely of and supported by said side walls, a member adjustable lengthwise of said drawer below the first-mentioned member, and resilient means connecting said members and urging the first-mentioned member downwardly toward said side walls.

7. In a file, the combination of a drawer having 85 side walls and a channel member extending lengthwise of said drawer and having flanges directed toward each other, an anchor member having parts disposed beneath said flanges and adjustable lengthwise of said channel member, a partition member extending transversely of and supported by said walls, and tension spring means connecting said partition member to said anchor member and urging said partition member 90 downwardly toward said side walls.

8. In a file, the combination of a drawer having 95 side walls, a member extending transversely of and above said side walls, rollers carried by said member and resting upon said side walls, and resilient means below said member to prevent upward displacement of said member and to hold said rollers in engagement with said side walls.

9. In a file, the combination with a drawer of 100 a follower device comprising an elongated member, cooperating means on the drawer and said member for retaining said member in a substantially transverse position relative to said drawer, said cooperating means being disengaged 105 upon removal of the member from the drawer, and resilient means mounted on and extending between said member and a portion of said drawer respectively to resiliently retain said 110 cooperating means in engagement.

10. A follower device comprising a pair of spaced members, means on one member adapted to engage portions of a file drawer to retain said member in a substantially transverse position 115 therein, the remaining member being adapted to be mounted in said drawer, and resilient means between said members for resiliently retaining the means on said first member in engagement.

11. In a file, the combination of a drawer having 120 side walls, and a vertically extensible device having one portion extending transversely of and supported by said side walls, and cooperating parts on the drawer and said device for holding said device in said drawer for slidably 125 engagement on said side walls.
